UNITED STATES PATENT OFFICE.

JAMES B. KIRBY, OF CLEVELAND, OHIO.

DESIGN FOR A VACUUM-CLEANER CASING.

44,846.

Specification for Design.

Patented Nov. 4, 1913.

Application filed September 15, 1913. Serial No. 789,899. Term of patent 14 years.

To all whom it may concern:

Be it known that I, JAMES B. KIRBY, a citizen of the United States, residing at Cleveland, county of Cuyahoga, and State of Ohio, have invented a new, original, and ornamental Design for a Vacuum-Cleaner Casing, of which the following is a specification, reference being had to the accompanying drawing, forming part thereof, in which,—

Figure 1 is a top view, and Fig. 2 is a side elevation of a vacuum cleaner casing showing my new design.

I claim:

The ornamental design for a vacuum cleaner casing, as shown.

JAMES B. KIRBY.

Witnesses:

F. C. MUSSUN,
E. M. FISHER.
